METHOD OF AND MEANS FOR VAPORIZING
HYDROCARBON LIQUIDS

Sam P. Jones, Dallas, Tex.

Application September 23, 1940, Serial No. 357,889

12 Claims. (Cl. 62—1)

This invention relates to new and useful improvements in methods of and means for vaporizing hydrocarbon liquids.

This application is filed as a continuation-in-part of my co-pending application Serial No. 757,686, filed December 15, 1934.

One object of the invention is to provide an improved method of and means for vaporizing hydrocarbons, such as liquefied gases, whereby said gases may be advantageously utilized as a fuel for motors, engines, burners or other devices.

An important object of the invention is to provide an improved apparatus for vaporizing hydrocarbon liquids, such as commercial butane, wherein the vaporization of the liquid is controlled by the volume of gas consumed by the device being supplied, that is, the volume of gas which is generated is in direct proportion to the load imposed on the apparatus, whereby a sufficient supply of gas is assured under all operating conditions.

A particular object of the invention is to provide an improved vaporizing apparatus for liquid hydrocarbons which consist of a mixture of various gases of different boiling points, such as for example, commercial butane; said apparatus being arranged so that the liquid is vaporized by applied heat, whereby a gas of a fixed B. t. u. value is at all times produced and also whereby the original mixture of the hydrocarbon liquid is substantially maintained.

Another object of the invention is to provide an improved apparatus, of the character described, wherein the hydrocarbon liquid is stored in a reservoir and a gas chamber is provided above the stored body to receive the gas produced through natural vaporization; the apparatus also having a vaporizing chamber which communicates with the reservoir to permit a portion of the liquid to be segregated and vaporized by an applied heat, together with means for supplying a gas-operated device with the gas from the vaporizing chamber under normal operating conditions and for supplying gas from the gas chamber only in the event that the gas supply from said vaporizing chamber is insufficient for the demand, whereby the original percentages of the various hydrocarbons in the hydrocarbon liquid, as well as the original boiling point of the liquid, are substantially maintained.

A further object of the invention is to provide an improved apparatus, of the character described, wherein a heat exchange surface is exposed to the liquid in the vaporizing chamber and the gas generated is controlled by the

volume of liquid contacting this surface which is, in turn, dependent upon the liquid level in said chamber; the apparatus being constructed so that the volume of the gas consumed by the device which is being operated, affects or controls this liquid level, whereby the volume of gas generated is in accordance with the demand.

Still another object of the invention is to provide an improved apparatus wherein the liquid reservoir is connected with the vaporizing chamber, with a one-way check valve mounted in the connection, said valve permitting a flow from the reservoir to the vaporizing chamber while preventing a reverse flow and being actuated by the differential in pressures in said reservoir and chamber, whereby a flow from the reservoir can occur only when the pressure in the vaporizer is below that in the reservoir.

Another object of the invention is to provide an improved method of vaporizing hydrocarbon liquids which consists in, confining a body of liquid and trapping the gases which rise therefrom through natural vaporization, heating a portion of the liquid by applied heat to produce gas in addition to the trapped gas rising from the stored body of liquid, and utilizing the gas vaporized by applied heat to supply a gas-operated device in its normal operation and using the trapped gas only when the vaporized gas is insufficient to supply the demand; the control of the gas flowing to the device from either source being affected by the pressures of the gas vaporized by applied heat and the gas rising from the stored body.

Still another object of the invention is to provide an improved method of and means for vaporizing hydrocarbon liquids wherein a heat exchange between the heated liquid in the vaporizer chamber and the stored body of liquid is produced so that the stored body of liquid is heated during normal operation by such heat exchange.

The construction designed to carry out the invention will be hereinafter described together with other features of the invention.

The invention will be more readily understood from a reading of the following specification and by reference to the accompanying drawings, in which an example of the invention is shown, and wherein:

Figure 1 is a longitudinal, vertical, sectional view of a vaporizing apparatus, constructed in accordance with the invention, for carrying out the improved method.

Figure 2 is an enlarged, section detail of the

dome or head, with which both the vaporizing chamber and the liquid reservoir are adapted to communicate.

Figure 3 is a horizontal, cross-sectional view, taken on the lines 3—3 of Figure 2.

Figure 4 is a detail of the feed line to a carburetor when the apparatus is employed to supply gas to said carburetor.

Figure 5 is a view, partly in elevation and partly in section of the pressure regulator,

Figure 6 is a partial elevation, illustrating the apparatus connected with an ordinary burner for supplying gas to said burner,

Figure 7 is a partial, longitudinal sectional view of the apparatus, illustrating the wall which separates the storage tank or reservoir from the vaporizer insulated with a suitable material,

Figure 8 is a sectional detail of another form of check valve,

Figure 9 is a view, partly in elevation and partly in section of a modified form of apparatus, and

Figure 10 is an enlarged detail of the check valve employed in this modification of the invention.

In the drawings, the numeral 10 designates an elongate tank or container, which is preferably cylindrical in shape and which has its ends closed by suitable caps or cover plates 11 and 12. As is the usual practice, the plates 11 and 12 are curved and a transverse plate 13, which has a curvature complementary to the curvature of the plate 11 is disposed within the tank adjacent said plate 11, whereby a transverse space or jacket 14 is provided at one end of the tank. The jacket has an inlet pipe 15 connected to its upper end and an outlet pipe 16 leading from its lower end (Figure 1). These pipes may be connected with a suitable hot water circulating system (not shown), whereby said water may be circulated through the jacket so as to heat the contents of the tank adjacent the plate 13.

A transverse partition 17 is disposed within the tank nearer the end where the water jacket 14 is located and this partition divides the interior of the tank into two compartments of unequal size. The larger compartment provides a liquid reservoir 18, while the smaller compartment formed between the partition 17 and the water jacket provides a vaporizing chamber or still 19. Communication is established between the liquid reservoir and the vaporizing chamber by means of a small opening 20 which is located in the lower portion of the transverse partition 17 and obviously, the liquid levels within the chamber and reservoir may be equalized through this opening. A liquid inlet pipe 21 is connected in the top of the tank 10 above the liquid reservoir and a transverse splash plate 22 may, if desired, be fastened centrally within the reservoir.

A cylindrical dome or head 23 is mounted on the tank 10 and is located above the partition 17, whereby said dome overhangs both the vaporizing chamber 19 and a portion of the liquid reservoir 18. The upper end of the vaporizing chamber 19 communicates with the interior of the dome or head 23 through an opening 24 which is provided in the top of the vaporizing chamber and which is located adjacent the upper end of the partition 17. A vertical riser pipe or conductor 25 has its lower end threaded into an opening 26 which leads from the liquid reservoir 18, said opening being disposed adjacent the upper end of the partition 17 and on the side opposite the opening 24 which leads from the vaporizing chamber 19. A check valve V is mounted on the upper end

of the riser or conductor 25 and includes a valve body 27 which is threaded onto said conductor. An annular seat 28 is provided within the upper end of the valve body and a valve member 29 is adapted to engage this seat. The valve member is provided with a depending stem 30 which is guided axially within the body 27 by means of a spider 31. Upward movement of the valve member 29 is limited by an enlarged head 32 which is formed on the lower end of the stem 30 and which strikes the spider 31 to prevent upward displacement of the valve member from the body 27. Above the valve V, the valve body is formed with a plurality of slots or openings 33 which prevent condensate from accumulating on the valve member 29 when said valve member is in its closed position. Manifestly, the weight of the valve member 29 will hold the same downwardly on the seat 28 and opening of the valve may be effected only by a pressure below said valve member sufficient to unseat said valve.

It is pointed out that the space above the liquid level within the reservoir 18 provides a gas storage chamber for storing the gas which rises from the body of liquid within said reservoir. Since the conductor 25 communicates with said storage chamber, it will be evident that the underside of the check valve 29 will be acted upon or exposed to the pressure of the gas in this chamber, such pressure tending to urge the valve member 29 upwardly toward an open position. The interior of the dome or head 23 provides a receiving chamber above the vaporizing chamber 19 and the pressure within this chamber is acting upon the upper end of the valve member 29. As explained, the weight of the valve member 29 tends to seat said valve and thus, the pressure within the receiving chamber, plus the weight of the valve, is urging the valve closed, while the pressure within the gas storage chamber G in the reservoir 18 is urging the valve toward an open position. Therefore, the valve member 29 is actuated solely by a differential in the pressures within the receiving chamber and the gas storage chamber. If the pressure within the dome 23 and the vaporizing chamber 19 is equal to the pressure within the gas chamber G, then the valve is closed, being held so by the weight of the valve member 29. However, as soon as the pressure within the gas chamber G overcomes the pressure within the receiving chamber formed by the dome 23, plus the weight of the valve member 29, the valve is opened to permit a flow of gas from the chamber G upwardly through the conductor 25 and into the receiving chamber. The fluid within the receiving chamber is conducted therefrom to an outlet pipe 34 which pipe is connected with fluid outlet 35 provided in the wall of the dome. A suitable hand-operated valve 36 may be connected between the outlet 35 and the outlet conductor 34, whereby the flow through the conductor may be regulated. The line 34 may extend to a burner, carburetor, engine, or any other gas-operated device for supplying gas thereto.

The apparatus is adapted for use in vaporizing or generating hydrocarbon liquid for liquefied gases and for the purposes of this description, it will be assumed that commercial butane is introduced into the tank 10. Liquefied gases which are in general commercial use consist of a mixture of a plurality of hydrocarbons, each of which have different boiling points at the same pressure. In the case of commercial butane, the same is in reality composed of varying percentages of butane, propane and iso-butane and may even

contain other hydrocarbons. Each of these hydrocarbons have different boiling points at the same pressure and the vapors or gases thereof contain varied heat values. Obviously, the various hydrocarbons and their proportions in the mixture control the boiling point of the mixture and also control the heat value of the vapor which is produced when the mixture is vaporized. When commercial butane is permitted to stand in a tank or other reservoir, under atmospheric pressure and temperature, vaporization within the reservoir will occur, due to the fact that the boiling point of liquid butane is about 33 degrees Fahrenheit. This vaporization will continue until a dormant condition is reached after which no further butane is vaporized so long as the temperature remains the same. For example, assuming that the atmospheric temperature is 60 degrees, vaporization of the liquid butane within the reservoir will continue until the pressure of the vapor or gas so produced has reached approximately 12 pounds, at which point sufficient heat has been extracted from the body of the liquid to bring about a dormant condition. So long as the temperature remains at 60 degrees, no further vaporization would occur.

Since the commercial butane is a mixture of a number of hydrocarbons, the vaporization which occurs when the liquid butane is permitted to stand in a reservoir under atmospheric conditions, is a vaporization of the lighter or more volatile fractions which are present in the mixture. Therefore, the propane and other lighter fractions vaporize first and the heavier ends remain in a liquid state. Some attempt has been made to draw off or remove the gases which are produced through natural vaporization for the purpose of operating various devices. These vapors or gases, as above explained, which rise above the liquid level in the reservoir consist predominantly of the lighter fractions which, in effect, are the most valuable constituents of the mixture. If these vapors are constantly withdrawn from the reservoir, it becomes obvious that the gases or vapors so withdrawn are not vapors consisting of a mixture of all of the hydrocarbons but rather, are vapors consisting of a mixture which contains the lighter fractions in a predominant volume. Therefore the gas or vapor which is initially withdrawn from the reservoir has a predetermined heat value; as the operation is continued, it will eventually occur that most of the lighter fractions are removed, with the result that the gases or vapors which are drawn from the reservoir as the liquid level falls therein have a different heat value because of the change in the mixture of such gases or vapor. For this reason, it is impractical and undesirable to attempt to operate a gas-operated device by means of vapors or gases which are drawn off of the reservoir, such gases having been formed by the natural vaporization which occurs within the interior of said reservoir.

The present apparatus contemplates the application of heat to a portion of the liquid body and this applied heat is sufficient to vaporize all of the hydrocarbons which are contained in the mixture. The vapors which are produced by this applied heat consist of a mixture of all of the constituents of the liquid and this vapor is supplied to the device which is to be operated thereby during the normal operation of such device. In this manner, the vapors which rise upwardly from the stored body of liquid are not depended

upon for operating the device connected with the apparatus during normal operation, with the result that vapors, having a constant heat value are conducted from the apparatus.

5 In the operation of the apparatus and in carrying out the improved method, the liquid hydrocarbon, that is, commercial butane, is introduced into the tank 10. It will be assumed that the atmospheric temperature is 60 degrees Fahrenheit and that it requires 2½ pounds of pressure to raise the valve member 29. Obviously, when the liquid is introduced into the tank, the liquid will flow through the opening 20 in the partition 17 and then into the vaporizing chamber 19, whereby the liquid levels within the chamber 19 and the reservoir 18 will be equalized, as shown by the dotted line A in Figure 1. It will also be assumed that the apparatus has been standing idle sufficiently long to be at atmospheric temperature and under these conditions, the pressure in the gas chamber G above the liquid level within the reservoir as well as the pressure within the vaporizing and receiving chambers above the liquid level in the vaporizing chamber will be equal, with the result that the weight on the valve member 29 holds the same in a seated position to shut off any communication between the receiving chamber and the gas storage chamber G within the tank 10. At this time, the heating and circulating system (not shown) by which hot water is circulated through the jacket 14 is idle.

30 Due to the physical properties of butane, a vaporization of a portion of the liquid in both the reservoir and the vaporizing chamber will occur until enough heat has been extracted from the liquid to bring about a dormant condition and as explained, such condition would occur when the pressure of the gas or vapor is approximately 12 pounds. So long as the atmospheric pressure 40 remains the same, no further vaporization would take place within the apparatus.

When it is desired to supply gas to a gas-operated device through the conductor 34, the valve 36 is manually actuated so as to permit 45 a flow of gas from the receiving chamber 23 into the conductor 34. As the gas in the top of the receiving chamber flows therefrom into this conductor, the pressure in the receiving chamber immediately begins to drop and such pressure drop upsets the dormant condition which 50 has been present within the apparatus, with the result that the liquid in the vaporizing chamber 19 begins to boil; this boiling immediately lowers the temperature in the vaporizing chamber. 55 The temperature drop is caused by the vaporization of the liquid in the chamber 19 as a result of the boiling action and heat is being removed from the liquid in the same manner as steam flowing from a boiler removes heat from said boiler. If the escape of gas from the receiving chamber and the vaporizing chamber continues without the application of an outside or auxiliary heat to the vaporizing chamber 19, the pressure within the receiving and vaporizing chambers will gradually fall and the liquid level within said vaporizing chamber will gradually rise. This rise in liquid level will be due to the fact that the gas pressure above the level in the vaporizing chamber 19 is less than the gas 60 pressure within the storage chamber G above the liquid level in the reservoir 18, thereby resulting in a flow of liquid from the reservoir, through the port 20 and into the vaporizing chamber 19. The lowering of the level within the reservoir 18 will result in an additional va-

porization of more of the liquid, whereby the vapor pressure in the gas storage chamber G is increased. As the withdrawal of gas from the receiving chamber is continued, the gas pressure in said chamber is finally reduced to a point where the pressure acting against the underside of the valve member 29, which is the pressure within the gas storage chamber G, is sufficient to lift the valve and when said valve is opened, gas is withdrawn from said storage chamber and thus outwardly through the conductor 34 to supply the device being operated. It is noted that as soon as the valve member 29 is unseated, the liquid level which has risen within the vaporizing chamber and the receiving chamber will not rise any further and this level is indicated by the dotted line B in Figure 1. Of course, the level to which the liquid will rise in the receiving chamber will be controlled by the differential pressure which is necessary to unseat the valve member 29, which differential pressure may be readily varied by changing the weight of the valve member 29.

From the above, it will be obvious that upon initial opening of the valve 36, gas is drawn from the receiving chamber 23 and if this gas is insufficient for the operation desired, then the valve member 29 is unseated to withdraw gas from the storage chamber G above the liquid in the reservoir 18. If the gas continued to be withdrawn through the valve 29, the temperature of both of the bodies of liquid in the reservoir 18 and the vaporizer 19 would be lowered and such lowering of the temperature would continue until about 33 degrees Fahrenheit was reached, at which temperature the vapor pressure would approximately equal atmospheric pressure and flow of gas would stop. However, in actual practice, the heating and circulating system begins to operate as soon as the valve 36 is opened, whereby hot water is circulated through the jacket 14 immediately upon the beginning of the withdrawal of gas from the receiving chamber.

The circulation of hot water through the jacket 14 results in heating the liquid butane within the vaporizing chamber 19, whereby gas is generated and rises upwardly into the receiving chamber 23. It might be that sufficient gas is generated by the application of heat to the vaporizing chamber to prevent the valve member 29 from opening, whereby no gas is withdrawn from the storage chamber G. However, if gas has been withdrawn from said storage chamber, the generation of an additional gas within the vaporizing chamber through applied heat, will raise the pressure within the receiving chamber 23, whereby the valve member 29 is closed. After the valve member 29 closes, the gas which is supplied to the conductor 34 is that which is generated by applied heat and the device which has connection with the conductor 34 is operated by this gas. It is noted that the heat which is applied to the vaporizing chamber is sufficient to vaporize all of the hydrocarbons which go to make up the mixture of the liquid butane, with the result that a gas having a predetermined heat value is produced and supplied through the conductor 34 to the device which is being operated. The arrangement is such that under normal operating conditions the liquid is vaporized by applied heat and the only time that gas is withdrawn from above the liquid level in the reservoir G is in starting or in the event that the heating system might fail and not supply sufficient gas for the purpose. This is an

important feature of the invention since it maintains the liquid mixture at substantially its original boiling point and supplies a gas of a substantially constant heat value to the device being operated.

Upon the initial operation of the vaporizer, substantially the entire surface of the curved plate 13 will be contacted by the liquid within the chamber 19 due to the fact that said liquid has risen within the vaporizing chamber, as has been explained. Therefore, a relatively large portion of liquid is heated, whereby a relatively large amount of gas or vapor is generated. In most instances, the gas generated when all of the contact surface 13 is engaged by liquid, is more than enough to supply the device being operated, with the result that the pressure within the receiving chamber 23 is gradually built up or increased. As this gas pressure within the receiving chamber increases, it acts downwardly on the liquid level in the vaporizing chamber 19 and serves to force said level downwardly within said chamber because the pressure within the receiving chamber 23 is greater than the vapor pressure within the storage chamber G above the liquid in the reservoir 18. As the liquid level is forced downwardly within the vaporizing chamber, a portion of the heated liquid from said chamber is passed back into the reservoir 18 through the opening 20 and this heated liquid serves to warm the liquid within the reservoir and restore, to some extent, the heat used in the vaporization of the gas above said liquid level. Also, the increased temperature of the liquid in the reservoir 18 acts to build up the pressure of the gas within the storage chamber G.

The lowering of the liquid level within the vaporizing chamber 19 reduces the amount of liquid which is in contact with the surface of the plate 13 and therefore less gas will be generated as the liquid level drops. The level will continue to fall until a balanced condition is reached, whereby the vaporizer will supply substantially the amount of gas or vapor which is being withdrawn through the conductor 34. In the event that an increased withdrawal from the receiving chamber occurs, the pressure in said receiving chamber will immediately be lowered, with the result that the liquid level in the vaporizing chamber 19 will again rise upwardly, whereby an increased amount of liquid will engage the contact surface of the plate 13. This will result in an automatic increase in the amount of gas or vapor which is generated. This arrangement makes the apparatus particularly adapted for use in supplying gas to an engine or other device which is subject to varying loads and obviously the amount of gas generated will be controlled in accordance with the load imposed or in accordance with the volume of gas which is being used. Of course, the rise and fall of the liquid level within the vaporizing chamber 19 sets up a more or less constant heat exchange between the heated liquid in the chamber 19 and the liquid within the reservoir 18 so that the pressure within the gas chamber G is maintained and is available in the event that the vaporizing equipment might fail to function properly.

From the foregoing, it will be obvious that a simple and efficient apparatus for generating and vaporizing liquefied gases is provided. The arrangement is such that upon initial operation and under excessive load, the gas is withdrawn from the storage chamber above the liquid level in the reservoir 18 but under normal operating

conditions, the liquid is vaporized through applied heat, whereby gas of a constant heat value is produced. By applying the heat to the liquid so as to generate or vaporize the gas, the mixture of the liquid is not changed and the gas which is produced and supplied to the device being operated is of substantially the same mixture throughout the entire operation. In other words, when the liquid level within the reservoir falls practically to the lower end of the tank, the gas being supplied is substantially the same as the gas which was produced upon initial operation. The provision of the check valve 27, which is actuated by the differential in pressures on each side thereof, permits a flow of gas from the gas chamber G under certain conditions; however, the check positively prevents the flow of gas or liquid from the vaporizing and receiving chambers back into the liquid reservoir 18. It is essential that flow in this direction be prevented in order to accomplish the result. The gas within the chamber G provides a reserve supply which is available for starting or under conditions where the load on the vaporizer becomes excessive. Whenever a portion of this reserve is used and more liquid within the reservoir 18 vaporized, the heat which is extracted from the body of liquid within the reservoir is replaced at least to some degree, due to the constant heat exchange between the heated liquid in the vaporizing chamber 19 and the liquid in the reservoir 18. The construction and arrangement of the vaporizing chamber permits the volume of vapor which is generated to be controlled by the load or by the volume of gas which is flowing outwardly through the conductor 34. In other words, if the volume of gas being supplied to the device increases or decreases, the liquid level within the vaporizing chamber 19 is automatically raised or lowered to increase or decrease the amount of gas generated in accordance with such change. Although the apparatus has been described as used with liquid butane, it is pointed out efficient results may be obtained with propane, or other similar hydrocarbons, or hydrocarbon mixtures. Other hydrocarbons having various boiling points may be employed to suit the particular climate wherein the apparatus is used.

The apparatus may be employed for supplying gas to any gas-operated device, such as an engine, burner or the like. In Figure 1, the apparatus is shown as connected with the carburetor 40 of an internal combustion engine (not shown). A pressure regulator 41 has connection with the conductor or outlet line 34 and said regulator is also connected through a pipe 42 with the lower end of the carburetor 40. The pipe 42 is provided with a check valve 43 in its underside to prevent condensation of any gas which might be standing in said pipe when the engine is halted. A vacuum pipe 44 connects the upper end on the carburetor with the upper half of the regulator 41 and positively controls the operation of said regulator. Obviously, the gas passes from the dome or receiving chamber 23 through the conductor 34, then through the pressure regulator 41 which maintains the pressure constant, and then the carburetor 40 of the engine.

The pressure regulator 41 is clearly shown in Figure 5 and comprises a lower pressure chamber 45 and an upper diaphragm case 46 which are secured together one above the other. The chamber 45 is connected with the carburetor 40 by the pipe 42, while the case 46 has connec-

tion with the carburetor through the vacuum line 44. The case 46 has a diaphragm 47 mounted therein and a spring 48 constantly exerts its pressure to hold the diaphragm in a lowered position. The diaphragm has a depending stem 49 which extends downwardly through the case 46 and into the pressure chamber 45 therebelow. The stem is in alignment with a stem 50 which extends upwardly from the diaphragm 51 mounted within the chamber 45. When the engine (not shown) is idle, the spring 48 holds the upper diaphragm 47 in its lowered position so that the lower end of the stem 49 engages the upper end of the stem 50 of the lower diaphragm 51, whereby the latter diaphragm is held downwardly against tension of a spring 52 therebelow and is thereby inoperative. However, when the engine is started, the suction created in the carburetor draws the upper diaphragm upwardly against the pressure of the spring 48, thereby raising the stem 49 away from the stem 50 of the lower diaphragm, permitting said lower diaphragm to operate normally.

With the lower diaphragm 51 in a raised position due to the tension of the spring 52, the stem 50 is raised. A pivoted crank 53 (Figure 5) has one arm extending through a slot in the stem 50 whereby as the stem is raised and lowered the other arm 54 of said crank is swung into and out of engagement with the end of a spring-pressed valve rod 55, which carries a valve 56 at its opposite end. The spring normally holds the valve 56 seated to close the aperture 57 into which the conductor 34 is connected, whereby the gas from the dome 23 cannot enter the head.

It will be apparent that when the engine (not shown) is idle, the upper diaphragm 47 holds the lower diaphragm in a lowered inoperative position. At such time, the stem 50 is in a lowered position and the arm 54 of the crank is engaging the end of the valve rod 55 to positively hold the valve 56 closed. When the engine is started, and the upper diaphragm moved upwardly to disengage the stem 49 from the stem 50, the spring 52 beneath the lower diaphragm 51 immediately raises said diaphragm. This swings the crank 53 so that the arm 54 disengages the valve rod 55. At such time, the valve 56 is held closed only by the spring and as soon as the gas pressure in the conductor 34 overcomes the pressure of this spring, the valve is automatically opened to admit gas into the carburetor. It is pointed out that this arrangement provides a safety feature in that the valve 56 never opens unless there is a sufficient gas pressure to operate the engine. In case there is a vacuum in the dome 23 the valve will of course, remain closed.

With the hook-up illustrated in Figure 1, the improved apparatus may be employed for supplying gas to an internal combustion engine. When so employed, the hot water system of the engine may be connected with the pipes 15 and 16 to circulate hot water through the jacket 14 and obviously as soon as the engine is started, auxiliary heat is applied to the liquid in the vaporizer chamber. It is noted that it would not be necessary to employ the particular pressure regulator shown in this figure and any suitable pressure regulator could be interposed between the conductor 34 and the carburetor 40.

The apparatus may also be employed for supplying other types of gas-operated devices and in Figure 6, the conductor 34 is shown as con-

nected through a pipe 60 with a gas burner 61. A suitable pressure regulator 62 is connected between the conductor 34 and the pipe 60 to control the pressure of the gas flowing to the burner 61. Also a hand-operated valve 63 may be connected in the pipe 60. Manifestly, the operation of the generating apparatus is not affected by the particular operation of any device to which gas is supplied.

The check valve 27 which is illustrated in Figure 1 has been described as operated by the differential in pressures on opposite sides thereof, but the invention is not to be limited to this particular type of valve. In Figure 8, a float operated valve 65 is shown. This valve is fastened to a curved arm 66 which is provided with a float ball 67 at its outer end, the opposite end of said arm being pivoted to the wall of a dome 23a on a pin 68. The curvature of the arm is such that when the valve 65 is closed or in a seated position, the float 67 depends into the vaporizing chamber 19. Whenever the liquid level in the vaporizing chamber 19 arises, the float 67 is raised to open the valve 65 and permit a flow of gas from the gas storage chamber G above the liquid level in the reservoir 18. The action or operation of the apparatus will be substantially the same as described with respect to the form shown in Figure 1. The use of a float operated valve permits the dome 23a to be made smaller than the dome 23 shown in Figure 1 and said float provides for maintaining a positive liquid level in the chamber 19, regardless of the liquid level in the reservoir 18. It also provides a positive opening and closing of the valve, controlled by the liquid level, rather than by a differential in pressures. In Figure 7, an insulating sheet 69 of asbestos, or similar material is shown fastened to the partition 17, whereby the heat within the vaporizing chamber 19 will not affect the liquid in the reservoir 18. This sheet may or may not be used, as desired.

In Figures 9 and 10, a slightly modified form of the invention is shown. In this form, a liquid storage reservoir 70 is made separate from a vaporizing chamber 71 and is connected at its lower end to the lower end of said chamber by means of an interconnecting pipe 72. The upper end of the vaporizing chamber 71 has connection with the upper end of the reservoir 70 through an angular pipe 73 and a suitable check valve 74 (Figure 10) is connected in this latter pipe. The valve 74 is the equivalent of the check valve 27 in the form shown in Figure 1. Instead of the water jacket 14 of the first form, the vaporizing chamber 71 is heated by a coil 75 which may be supplied with hot water from a suitable source. Manifestly, the operation of this form of the invention will be substantially the same as the first form, the liquid level within the vaporizing chamber rising and falling in accordance with the amount of gas which is drawn off through an outlet conductor 34a which leads from the upper end of the chamber 71. The check valve 74 permits a flow of gas from the reservoir 70 only when the supply of gas within the upper end of the vaporizing chamber 71 is insufficient to supply the demand. Also, the check valve positively prevents any flow at any time from the vaporizing chamber through the pipe 73 and back into the reservoir 70.

The foregoing description of the invention is explanatory thereof and various changes in the size, shape and materials, as well as in the details of the illustrated construction may be made,

within the scope of the appended claims, without departing from the spirit of the invention.

What I claim and desire to secure by Letters Patent is:

1. The combination with the carburetor, of a vaporizing apparatus comprising, a liquid reservoir having a gas space for accumulating gas vaporized from the body of liquid, a vaporizing chamber connected with the reservoir, a receiving chamber connected with both the gas space and vaporizing chamber, means for controlling the supply of gas from the gas space into the receiving chamber, a gas supply pipe leading from the receiving chamber, a pressure regulator connected to the supply pipe, a pipe line connecting the regulator with the carburetor whereby gas is conducted from the receiving chamber to said carburetor, a valve in said line adapted to be opened to admit air into the line when flow through the line is stopped and said gas contracts in volume, whereby the admitted air admixes with the gas in said line to prevent condensation thereof when the apparatus is idle, and means for automatically cutting off the gas from the supply pipe to the regulator when there is insufficient pressure in the receiving chamber.

2. The method of vaporizing liquefied gas for use in an internal combustion engine which consists in, confining a body of liquid, accumulating the gases rising from said body of liquid, segregating a portion of the liquid, heating said segregated portion by the heat derived from the engine to cause vaporization to produce gas in addition to the accumulated gas, and utilizing the heated portion of the liquid during the operation of the engine for heating the body of liquid to maintain the same at a temperature sufficient for vaporization.

3. The method of vaporizing liquefied gas for use in an internal combustion engine which consists in, confining a body of liquid, accumulating the gases rising from said body of liquid, segregating a portion of the liquid, heating said segregated portion by heat derived from the engine to cause vaporization to produce gas in addition to the accumulated gas and utilizing the heated portion of the liquid during the operation of the engine for heating the body of liquid through a heat exchange, and controlling the heat exchange by the pressure of the gas generated from the segregated and heated portion of the liquid.

4. The method of vaporizing liquefied gas for supplying a gas operated device which includes, confining a body of liquefied gas, accumulating gas arising from said body, temporarily utilizing said accumulated gas, conducting a portion of said liquid through a zone of continuous heat to vaporize said liquid portion and provide an operating supply of gas, varying the rate of heat transfer from the heat source to the liquid portion to be vaporized solely by the rise and fall of the liquid being vaporized which is induced by pressure variations resulting from the fluctuations in the consumption of the gas, and shutting off the communication with the accumulated gas when the supply of operating gas is sufficient.

5. The method as set forth in claim 4 wherein in the heating of the conducted liquid portion is continuous regardless of pressure or volume fluctuations.

6. The method of vaporizing liquefied gas as set forth in claim 4 wherein the back flow of the liquid to the body is unrestrained so that

pressure increases may freely depress the liquid being vaporized.

7. The method of vaporizing liquefied gas for supplying a gas operated device which includes, confining a body of liquefied gas, accumulating gas arising from said body, conducting liquid from the bottom of said body through a zone of continuous heat to vaporize said liquid and provide a supply of service gas, by-passing accumulated gas for temporary use into the service gas supply, and utilizing the pressure of the service gas to permanently shut off the flow of accumulated gas to the service gas during normal operation of the system.

8. The method of vaporizing liquefied gas for supplying a service line which includes, confining a body of liquefied gas and maintaining sufficient vaporization to accumulate only a supply of auxiliary gas, conducting the liquid through a segregated zone and heating said segregated liquid to provide an adequate supply of service gas during normal operation of the method, controlling the heating of the segregated liquid by the rise and fall thereof, supplying the auxiliary gas to the service line temporarily when the supply of service gas is inadequate, and controlling the supply of auxiliary gas to the service line and preventing its return to the liquid body by pressure variations in the service line.

9. A vaporizing apparatus for liquefied gases including, a liquid containing reservoir having a gas space for accumulating gas vaporized from the body of liquid, a vaporizing container connected with the reservoir below the gas space thereof, said connection being open to provide back and forth flow between the reservoir and the container, a receiving container connected with the vaporizing container and receiving the regular operating gas of the apparatus therefrom, a separate one-way connection extending from the gas space of the reservoir to the receiving container for discharging gas only from the gas space into the receiving chamber, means for heating the liquid in the vaporizing container co-acting with the rise and fall of the liquid therein to vary the rate of heat transfer from the heat source to the said liquid, and means for shutting off the flow of gas back through the connection from the receiving container to the gas space of the reservoir to cause the fluctuating pressure of the gas in the receiving and vaporizing containers to exert its entire back pressure on the liquid in the vaporizing container to control the level of said liquid therein and the amount of liquid contacting said heating means.

10. A vaporizing apparatus for liquefied gases including, a reservoir for containing a body of liquefied gas, a vaporizing container having a

back and forth flow connection therewith, an upright heater for heating the liquid in said container, conducting means for the gas vaporized in said container, means for discharging accumulated gas from the reservoir to the conducting means, and means for positively shutting off flow of gas from the conducting means to the reservoir to apply the full gas pressure in the vaporizing container to the liquid therein to vary the height of said liquid with relation to said heater to control the vaporizing of liquid in said container.

11. In a vaporizing apparatus, the combination with the carburetor of an internal combustion engine, a liquid containing reservoir having a gas space for accumulating gas vaporized from the body of liquid, a vaporizing container connected with the reservoir below the gas space thereof, said connection being open to provide back and forth flow between the reservoir and the container, a receiving container connected with the vaporizing container and receiving the regular operating gas of the apparatus therefrom, a gas supply conductor extending from the receiving container to the carburetor, a separate one-way connection extending from the gas space of the reservoir to the receiving container for discharging gas only from the gas space into the receiving container, means for heating the liquid in the vaporizing container co-acting with the rise and fall of the liquid therein to vary the rate of heat transfer from the heat source to the said liquid, and means for shutting off the flow of gas back through the connection from the receiving container to the gas space of the reservoir to cause the fluctuating pressure of the gas in the receiving and vaporizing containers to exert its entire back pressure on the liquid in the vaporizing container to control the level of said liquid therein and the amount of liquid contacting said heating means.

12. In a vaporizing apparatus, the combination with the carburetor of an internal combustion engine, a reservoir for containing a body of liquefied gas, a vaporizing container having a back and forth flow connection therewith, an upright heater for heating the liquid in said container, conducting means for the gas vaporized in said container to the carburetor, means for discharging accumulated gas from the reservoir to the conducting means, and means for positively shutting off flow of gas from the conducting means to the reservoir to apply the full gas pressure in the vaporizing container to the liquid therein to vary the height of said liquid with relation to said heater to control the vaporizing of liquid in said container.

SAM P. JONES.
